(57) **CLAIM**

The ornamental design for a medicine administration device, as shown and described.

DESCRIPTION

FIG. 1 is a front view of a medicine administration device; FIG. 2 is a rear view of the medicine administration device design thereof;

FIG. 3 is a left view of the medicine administration device design thereof;

FIG. 4 is a right view of the medicine administration device design thereof;

FIG. 5 is a first perspective view of the medicine administration device design thereof;

FIG. 6 is a second perspective view of the medicine administration device design thereof;

FIG. 7 is a third perspective view of the medicine administration device design thereof;

FIG. 8 is a fourth perspective view of the medicine administration device design thereof;

FIG. 9 is a fifth perspective view of the medicine administration device design thereof; and,

FIG. 10 is a front view of the medicine administration device, shown in use and in an alternate state.

1 Claim, 10 Drawing Sheets
